FOLDING GRAPNEL ANCHOR

Bror Tamm, Quincy, Mass.

Application May 5, 1948, Serial No. 25,167

4 Claims. (Cl. 114—207)

1

My present invention relates to anchors, and more particularly to the grapnel type of anchors. Such grapnel anchors are formed with a shank and a plurality of prongs or flukes extending from the end or crown of the shank and at divergent angles.

These anchors are of light weight, strong, easily constructed, and most efficient in holding power, but are subject to the disadvantage of not being easily stowed. Thus a standard type of grapnel, whether of three, four, or five-pronged construction, always had the arms rigid, usually with sharp points at the end of each fluke, and was a constant menace to crew and rigging when not in use.

I have discovered a novel and efficient method of so designing and constructing a grapnel anchor as to overcome the objectionable features above briefly outlined, and to enable the prongs, arms, or flukes of a grapnel type of anchor to be folded, collapsed, or housed into compact form, for stowing on deck or below decks, and for packaging, transporting, or shipping in a compact form.

In carrying out my invention of a foldable grapnel, I maintain all the advantages of the grapnel type, of simple and economical construction, light weight, and efficient holding power, together with the desirable features of folding the separate prongs or arms in a compact nested position so that it can be laid flat on deck, or stowed in a small space, and without the prongs projecting to injure the crew or catch articles.

I have designed my folding construction so as to permit instant change from operative or expanded position to inoperative or folded position, without the use of bolts, keys, or the like as now required in anchors having a folding stock, thus saving time and work especially in an emergency.

The change from operative to inoperative position is accomplished by a quarter turn, viz., 90° of the flukes, and I arrange the flukes in pairs, which permits the quarter-turn operation. I also provide bracing and locking elements which will hold the pairs of flukes braced and locked in either folded position for stowing, or expanded relation for operative use.

By providing a feasible folding grapnel anchor, I have greatly enlarged the scope and field of usefulness of this highly desirable type of ground tackle. Heretofore, grapnels were restricted to use in small boats, but my invention enables grapnels of relatively large size to be employed, because of the advantages of folding and stowing. Thus, a greatly increased range of grapnel anchors in length, diameter, of holding flukes, and

2

weight can be offered to the boatman, sailor, yachtsman, and fisherman.

The relatively light weight of the grapnel type, and great holding power, wherein two flukes always dig into the holding ground, enable my improved anchor to be made out of light metal or alloys, as well as of iron or compositions of both.

Referring to the drawings illustrating several modifications of my invention:

10 Fig. 1 illustrates one form of my grapnel in folded or nested position;

Fig. 2 illustrates the same in expanded position;

Fig. 3 is a cross-sectional view on the line 3—3 of Fig. 2;

Fig. 4 is an enlarged detailed view of the locking brace;

Fig. 5 is a view of a modification in folded position;

20 Fig. 6 is a view of this form in expanded or operative position;

Fig. 7 is a cross-sectional view on the line 7—7 of Fig. 6;

Fig. 8 is an enlarged detail of the holding and

25 locking braces;

Fig. 9 is a view of a simpler modification in nested position;

Fig. 10 is a view of this form in expanded position;

30 Fig. 11 is a cross-sectional view on the line 11—11 of Fig. 10, and

Fig. 12 is an enlarged detail of the holding brace.

Referring to the form shown in Figs. 1, 2, 3, and 4, I arrange two pairs of flukes and arms, a slightly longer and wider pair having arms 2 and 4 united by a U-shaped portion 5, and at the opposite ends branching into angular flukes or prongs 7 and 8, ending in palms 10 and 12. The co-operating pair comprise shanks or arms 15 and 16 united at 18, and with divergent prongs 19 and 20 ending in palms 21 and 22. The shanks 15 and 16 are bent inwardly, as indicated at 25, to facilitate the 90° turning action, as will be explained.

At the portion of the shanks just above the bends 25 is a cross-bar 26 which will strike a curved bar 27 extending between the wider spaced shanks 7 and 8 and prevent complete separation of the two pairs during the longitudinal and quarter-turn movement when shifting from folded or inoperative position to expanded or operative position. A short brace 29 is preferably fitted between the shanks 15 and 16 where the prongs 19 and 20 start to branch out to give

strength and rigidity to the same, being welded together. Also welded to the wider shanks **2** and **4** is a fluted brace **30** encircling at all times the pair of arms **15** and **16** and constituting holding and locking braces where both pairs are in right-angled position ready for use, as shown in Figs. 2 and 3.

A top brace **31** is also provided, being similarly fluted to the brace **30** but on a shorter diameter. A shackle or hook **33** to which the rod or cable **34** is fastened locks the two pairs together by engaging the U-shaped portions **5** and **18**.

Thus, with the pairs in nested position as shown in Fig. 1, a longitudinal motion until the cross-brace **26** strikes the curved brace **27** is effected; and thereupon a quarter-turn enables the bent parts **25** to turn within the encircling fluted brace **30**, and then a return longitudinal motion enables the shanks **15** and **16** to ride in the side flutes of braces **30** and **31**, holding and bracing all four shanks in expanded and operative position. Snapping in the hook **33** couples the anchor ready for use. Reverse movement provides for the nesting or folding.

Referring to the form shown in Figs. 5, 6, 7, and 8, a similar construction of pairs of shanks, prongs, and palms are used but the interlocking device to keep the two pairs from being completely separated is different. In this form, the crosspiece **35** welded to the top portion of the narrower pair of shanks **15** and **16** just above the bent portions **75** is of S-shaped form and will act as a stop or limit of lengthwise separating movement when the quarter-turning action is to be made.

Referring to the form shown in Figs. 9, 10, 11, and 12, this is a much simpler form and permits complete lengthwise separation of the pairs to be effected, before the quarter-turning action, either for expanding or for nesting. As shown, the wider pair of shanks **40** and **41** united at **42**, and with angular prongs **43** and **44** ending in points or with palms **45**, are held in rigid position by fluted braces **46** and **47**.

The narrower pair of shanks **50** and **51**, united at **52**, are formed without any bent sections **75** as in the prior forms. These shanks have straight welded braces **54** and **55**. Relative longitudinal motion from either nested or expanded position until the pairs are completely separated is made, as shown in Fig. 12, whereupon the 90°

or quarter-turn is made and the pairs reassembled. In this form, the pairs can be separately stowed or used, as well as nested together as shown in Fig. 9.

In all forms a sturdy, strong, but light and efficient construction is effected, with facility for quick change from operative to inoperative, or reverse, position without keys, wrenches, or tools.

I claim:

1. A folding grapnel anchor of the kind described, comprising a plurality of shanks and flukes arranged in pairs, each pair consisting in a double shank, with each shank having a fluke at one end, a loop uniting the shanks of each pair at the end opposite said flukes, a fluted brace adjacent the flukes welded to the double shanks of one pair, and having fluted recesses at right angles thereto to detachably receive the double shanks of the adjacent pair, and to be interlocked into operative or inoperative position by a ninety degree turning action.

2. A folding grapnel of the kind described, comprising two pairs of flukes, each pair comprising double shanks united at the end opposite to the flukes, braces rigidly secured to one pair of double shanks adapted to interlock with the double shanks of the opposite pair by a relatively lengthwise and quarter-turn movement.

3. A folding grapnel of the kind described, comprising two pairs of flukes, each pair having shanks united at the end opposite to the flukes, one pair being of slightly greater length whereby the shorter may be nested therein, a brace on the longer pair partly encircling the shorter whereby a relative lengthwise and quarter-turn action will shift said pairs into operative or inoperative position.

4. A folding grapnel of the kind described, comprising two pairs of flukes, each pair having shanks united at the end opposite to the flukes, one pair being of slightly greater length whereby the shorter may be nested therein, a locking brace on the longer pair partly encircling the shorter whereby a relative lengthwise and quarter-turn action will shift said pairs into operative or inoperative position and be automatically locked in said relative positions by the action of the locking brace.
